REINFORCED PATCH POCKET

Charles D. Williamson, Fort Worth, Tex.

Application July 13, 1951, Serial No. 236,487

7 Claims.

(Cl. 2—248)

1

This invention relates to a reinforced patch pocket and particularly concerns a reinforced patch pocket for a garment of the trousers type such as the hip pocket of an overall.

Usually, the hip pocket of an overall is used by the wearer for the purpose of carrying tools of various types. When so used, there is a tendency for sharp edged tools to jab holes in the side and bottom of the pocket. To avoid jabbing holes in the bottom of the hip pocket, the ordinary type overall hip pocket has a bottom reinforcement panel on the back of the pocket panel at the bottom thereof. A double row of stitching secures the top of the reinforcement panel to the pocket and a margin at the bottom of the pocket panel is crimped over the bottom of the reinforcement panel. By suitable stitching, the patch pocket is secured to the overall.

As it is customary for the reinforcement panel to extend across only the lower portion of the pocket panel, such reinforcement does not protect the pocket from holes jabbed along the sides of the upper portion of the pocket panel.

To avoid these difficulties, a major object of this invention is to provide a reinforced patch pocket for the hip pocket of an overall in which the entire sides of the pocket panel are reinforced.

More particularly, an object of this invention is to provide a hip pocket for an overall with side and bottom reinforcement panels, which panels are so arranged that little additional material is required and the panels may be readily placed in the pocket.

In the attainment of these objects, one feature of the invention resides in the provision of a bottom reinforcement panel which is narrower than the main pocket panel with side reinforcement panels extending from top to bottom of the pocket and overlying the side edges of the bottom reinforcement panel. Another feature of the invention resides in the stitching from side edge to side edge of the main pocket panel along the top of the bottom reinforcement panel as well as stitching from the top edge of the main pocket panel along the inner side edges of the side reinforcement panels to the bottom edge of the main pocket panel.

Still another feature of the invention resides in the folding over of the top edges of the main pocket panel and the side reinforcement panels with a double row of stitching securing the folded top edges to the main pocket panel.

Other objects and advantages of the invention will become apparent from the following specification taken in conjunction with the accompanying drawings wherein:

Fig. 1 is a rear elevation view of a pair of overalls or work trousers showing two hip pockets embodying the invention in its preferred form;

Fig. 2 is an exploded view of the hip pocket shown in Fig. 1 with the parts shown in disassembled relation;

2

Fig. 3 is an elevational view of the back of the main pocket panel shown in Fig. 2 with the bottom reinforcement panel secured thereon;

Fig. 4 is a view similar to Fig. 3 but showing the side reinforcement panels secured to the back of the main pocket panel.

Fig. 5 is also similar to Figs. 3 and 4 but shows the further step in the fabrication of the pocket with the top edges of the side panels and the main panel crimped over the back of the main panel;

Fig. 6 is a view showing the fabricated reinforced patch pocket positioned and secured to a garment;

Fig. 7 is a vertical sectional view of the pocket embodying the invention taken along the line 7—7 of Fig. 6; and

Fig. 8 is a horizontal sectional view taken along the line 8—8 of Fig. 6.

In the form of the invention illustrated in the drawings, hip pockets 11, 11 are shown secured to the back of a pair of overalls 12. These hip pockets 11 are formed in accordance with the present invention and each has a main pocket panel 13 of a shape corresponding to the desired shape of the pocket. However, the size of the main pocket panel is somewhat larger than the desired size of the pocket for a reason subsequently to be explained. Preferably, side edges 14 and 15 of main pocket panel 13 merge with bottom edge 16 through curved corners 17 and 18, respectively. To avoid too much bulk at the upper corners, the corner of top edge 19 with side edges 14 and 15 may be cut at an angle as indicated by the angular corners 21 and 22, respectively. Thus, main pocket panel 13 is of generally rectangular shape having rounded bottom corners 17 and 18 and angular top corners 21 and 22.

Forming a part of the reinforced pocket is a bottom reinforcement panel 23 which is also preferably of rectangular shape. Bottom edge 24 of the bottom reinforcement panel 23 is preferably spaced slightly above bottom edge 16 of the main pocket panel 13. Side edges 25 and 26 of the bottom reinforcement panel 23 are spaced inwardly from the respective side edges 14 and 15 of the main pocket panel. Bottom reinforcement panel 23 is secured to the back face of the main pocket panel 13 by a double row of stitches 27 extending between side edges 14 and 15 of the main pocket panel and along the portion of bottom reinforcement panel 23 adjacent top edge 28 thereof.

In addition to bottom reinforcement panel 23, a pair of side reinforcement panels 31 and 32 are provided. Side reinforcement panel 31 has its outer edge 33 extending along but spaced inwardly from side edge 14 of the main pocket panel 13. Curved bottom 34 of side reinforcement panel 31 conforms generally to the curvature of corner 17 of the main pocket panel, but

is spaced inwardly from the edge at that corner. Top edge 35 of the side reinforcement panel 31 extends to a point spaced slightly below the top edge 19 of the main pocket panel. Inasmuch as the side edge 33 and inner side edge 36 of the side reinforcement panel 31 converge slightly upwardly, with the outer side edge 33 extending along side edge 14 of the main pocket panel, inner side edge 36 of the side reinforcement panel 31 is disposed at an angle inclined upwardly and outwardly with respect to the main pocket panel 13. The lower portion of inner edge 36 of side reinforcement panel 31 overlies side edge 25 of bottom reinforcement panel 23. At this point, the pocket panel has three thicknesses, namely, the main pocket panel, the bottom reinforcement panel, and the side reinforcement panel. Stitching 37, extending from top edge 19 along inner side edge 36 of the side reinforcement panel 31 and along side edge 25 of bottom reinforcement panel 23 to the bottom edge 16 of the main pocket panel, secures the side reinforcement panel 31 to the back face of the main pocket panel 13 and to the side portion of the bottom reinforcement panel 23.

Similarly, outer side edge 38 of side reinforcement panel 32 extends along but is spaced inwardly from side edge 15 of the main pocket panel 13. Bottom edge 39 conforms generally to the curvature of bottom corner 18 of the main pocket panel, and top edge 41 of the side panel is spaced from the top edge 19. Along its longer portion, side reinforcement panel 32 has its inner side edge 42 overlying the side edge 26 of the bottom reinforcement panel 23. Side edges 38 and 42 of the side reinforcement panel 32 converge upwardly in the same manner as side reinforcement panel 31. Stitching 43 extends from top edge 19 along inner side edge 42 to bottom edge 16 of the main pocket panel. Due to the upward convergence of the side edges of the respective side reinforcement panels 31 and 32, their inner side edges 36 and 42 diverge upwardly toward the top of the pocket. The stitching 43 along inner edge 42 of side reinforcement panel 32 not only secures this side reinforcement panel to the back face of the main pocket panel but also secures it to bottom reinforcement panel 23 along the side edge 26 thereof.

For the purpose of finishing the top edge of the pocket to provide a smooth and durable exposed top edge, the top edge portions of the main pocket panel 13 and the side reinforcement panels 31 and 32 are crimped along a line spaced below these top edges. Such a line is indicated in dot and dash lines at F in Fig. 4. With the top edge portions of the main pocket panel and the side reinforcement panels crimped over the back face of the main pocket panel, a double row of stitching 45 secures the crimped portion to the unfolded portions. As will be noted in Fig. 5, the diagonal cut corners 21 and 22 prevent an accumulation of excess material in the upper corners of the pocket. As shown in Fig. 5, the patch pocket is completed with the exception of the assembly of the pocket onto the overalls. As it appears in Fig. 5, the main pocket panel has bottom reinforcement panel 23 secured to its back face by stitching extending between the sides of the main pocket panel along the top edge of the bottom reinforcement panel. Side reinforcement panels 31 and 32 extend along the respective sides of the main pocket panel and have their inner side edges secured by stitching extending from the top edge of the main pocket

panel to the bottom edge thereof. This stitching along the inner side edges of the side reinforcement panels secures them to the bottom reinforcement panel 23 and also secures the side edge portions of this bottom reinforcement panel to the main pocket panel. The top edges of the main pocket panel and side reinforcement panels are crimped over the back of the main pocket panel and secured by stitching extending between the sides of the main pocket panel.

Before assembly onto the overalls, the marginal portions of the main pocket panel, extending outwardly at the sides and bottom of the reinforcement panels, are crimped over the side edges 33 and 38 of the side reinforcement panels as well as the bottom edges 34 and 39 thereof. Also, the bottom marginal portion of the main pocket panel is crimped over the bottom edge 24 of the main pocket panel. These crimped side and bottom edges of the main pocket panel are then secured by a double row of stitching extending along the sides of the side reinforcement panels, the bottoms of the side reinforcement panels and along the bottom of the bottom reinforcement panel. This stitching not only secures the main pocket to the overall garment, but also secures the side and bottom edges of the reinforcement panels to the main pocket panel.

When assembled on the overall garment, the reinforced patch pocket of the present invention provides reinforced sides and a reinforced bottom, extending from the stitching securing the pocket to the garment inwardly toward the center of the pocket. This reinforcement along the sides of the pocket as well as the bottom thereof prevents holes from being worn in the pocket when sharp tools are jabbed into the reinforced part. With this construction, the pocket will wear longer than a pocket having only a bottom reinforcement because the pocket is stronger and the sides will stand more punishment than pockets of conventional design. Inasmuch as the side reinforcement extends all the way from the top to the bottom of the pocket, it is unnecessary to have a bottom reinforcement panel extending entirely across the bottom of the pocket. The vertical stitching securing the side reinforcement panels to the main pocket panel further reinforces and strengthens the pocket itself. In addition, the particular arrangement of the inner side edges of the side reinforcement panels overlying the side edges of the bottom reinforcement panel not only strengthens the pocket itself but provides a construction which is easily fabricated without materially adding to the cost of the pocket.

In the foregoing description, a preferred embodiment of the invention has been described in detail, but it is to be understood that variations in this particular construction may be made without departing from the invention. Therefore, this description is intended to be constructed as illustrative and not in a limiting sense. Having thus described the invention, what is claimed as new is:

1. In a garment of the trousers type, a reinforced patch pocket comprising a main pocket panel of a shape corresponding to the shape of the desired pocket, a bottom reinforcement panel having its upper edge secured to the back of said main pocket panel and having its side edges spaced inwardly from the side edges of said main pocket panel, and side panels having their inner edges secured to the back of said main pocket panel at the opposite sides thereof and having

their respective lower portions overlying said bottom reinforcement panel.

2. In a garment of the trousers type, a reinforced patch pocket comprising a main pocket panel of a shape corresponding to the desired shape of the pocket, a bottom reinforcement panel having its upper edge stitched to the back of said main pocket panel and having its side edges spaced inwardly from the side edges of said main pocket panel, and side panels having their inner edges stitched to the back of said main pocket panel and extending from a point near the top edge of said main pocket panel to a point overlying the side edges of said bottom reinforcement panel, the top edges of said main pocket panel and said side reinforcement panels being crimped over the back of said main pocket panel and stitched thereto.

3. In a garment of the trousers type, a reinforced patch pocket comprising a main pocket panel of a shape corresponding to the shape of the desired pocket, a bottom reinforcement panel at the bottom of the back of said main pocket panel, the side edges of said bottom reinforcement panel being spaced inwardly from the side edges of said main pocket panel, stitching securing the top edge of said bottom reinforcement panel to said main pocket panel and extending between the side edges of said main pocket panel, a pair of side reinforcement panels extending from points near the top edge of said main pocket panel downwardly to overlie the side edges of said bottom reinforcement panel, and stitching extending from the top edge of said main pocket panel to the bottom edge thereof securing the inner side edges of said side reinforcement panel to the back of said main pocket panel, the top edges of said main pocket panel and said side reinforcement panels being crimped over the back of said main reinforcement panel and stitched thereto.

4. In a garment of the trousers type, a reinforced patch pocket comprising a main pocket panel of a shape corresponding to the desired shape of the pocket, a bottom reinforcement panel having its upper edge secured to the back of said main pocket panel and having its side edges spaced inwardly from the side edges of said main pocket panel, and a pair of side reinforcement panels extending from points adjacent the top edge of said main pocket panel downwardly and overlying the side edges of said bottom reinforcement panel, the side edges of said main pocket panel and the bottom edge thereof being crimped over said reinforcement panels and secured by stitching to the garment.

5. A reinforced patch pocket comprising a main pocket panel of a shape and size corresponding to but larger than the desired pocket, a bottom reinforcement panel narrower and shorter than said main pocket panel, said bottom reinforcement panel being positioned on the back of said main pocket panel with its bottom and side edges spaced from the bottom and side edges of said main pocket panel, stitching securing the top edge of said bottom reinforcement panel to said main pocket panel and extending to the side edges of said main pocket panel, a pair of side reinforcement panels disposed on the back of said main pocket panel with their outer side edges respectively extending along and spaced inwardly from the opposite side edges of said main pocket panel, the lower portions of said side reinforcement panels overlying the side edges of said bottom reinforcement panel to said main pocket panel and stitched thereto.

ment panel, and stitching securing the inner side edges of said side reinforcement panels to said main pocket panel and extending from the top edge to the bottom edge of said main pocket panel.

6. A reinforced patch pocket comprising a main pocket panel of a shape and size corresponding to but larger than the desired pocket, a bottom reinforcement panel narrower and shorter than said main pocket panel, said bottom reinforcement panel being positioned on the back of said main pocket panel with its bottom and side edges spaced from the bottom and side edges of said main pocket panel, stitching securing the top edge of said bottom reinforcement panel to said main pocket panel and extending to the side edges of said main pocket panel, a pair of side reinforcement panels disposed on the back of said main pocket panel with their outer side edges respectively extending along and spaced inwardly from the opposite side edges of said main pocket panel, the lower portions of said side reinforcement panels overlying the side edges of said bottom reinforcement panel, stitching securing the inner side edges of said side reinforcement panels to said main pocket panel and extending from the top edge to the bottom edge of said main pocket panel, the top edges of said main pocket panel and said side reinforcement panels being crimped over the back of said main pocket panel, and stitching extending between the side edges of said main pocket panel securing the crimped portion of the top edge thereof and the crimped portion of the top edges of said side reinforcement panels to said main pocket panel.

7. A reinforced patch pocket comprising a main pocket panel of a shape and size corresponding to but larger than the desired pocket, a bottom reinforcement panel narrower and shorter than said main pocket panel, said bottom reinforcement panel being positioned on the back of said main pocket panel with its bottom and side edges spaced from the bottom and side edges of said main pocket panel, stitching securing the top edge of said bottom reinforcement panel to said main pocket panel and extending to the side edges of said main pocket panel, a pair of side reinforcement panels disposed on the back of said main pocket panel with their outer side edges respectively extending along and spaced inwardly from the opposite side edges of said main pocket panel, the lower portions of said side reinforcement panels overlying the side edges of said bottom reinforcement panel, stitching securing the inner side edges of said side reinforcement panels to said main pocket panel and extending from the top edge to the bottom edge of said main pocket panel, the side edges and bottom edge of said main pocket panel being crimped to overlie said reinforcement panels, and stitching extending around the sides and bottom of the pocket securing said folded side and bottom edges to the backs of said reinforcement panels.
